UNITED STATES PATENT OFFICE

HARRY HERTZBERG, OF BROOKLYN, NEW YORK, ASSIGNOR, BY MESNE ASSIGNMENTS, TO THE M. PROPP CO. INC., OF NEW YORK, N. Y., A CORPORATION OF NEW YORK

ELECTRIC-LAMP SOCKET

Application filed November 30, 1926. Serial No. 151,629.

This invention relates to lamp sockets and is directed to a lamp socket of improved construction having incorporated in its structure means for dimming the light of a lamp connected therewith.

An object of the invention is to provide a lamp socket of the character described having a casing formed entirely of molded insulating composition and constructed to permit such arrangement and disposition therein of the parts of the dimming means and its control mechanism as to provide a simple and compact device of neat appearance.

Another object of the invention is to generally improve the construction of lamp sockets of the character described to make for high economy in material and parts so as to facilitate large scale production and yet provide a compact, rugged structure which shall be relatively cheap to manufacture, and practical and efficient in operation to a high degree.

Other objects of this invention will in part be obvious and in part hereinafter pointed out.

The invention accordingly consists in the features of construction, combinations of elements, and arrangement of parts which will be exemplified in the construction herein-after described, and of which the scope of application will be indicated in the following claims.

In the accompanying drawing, in which is shown one of the various possible illustrative embodiments of this invention,

Fig. 1 is a top plan view of the device embodying the invention, showing the plug cap portion removed to expose the dimming means and its control mechanism.

Fig. 2 is a cross-sectional view of the improved device corresponding to a section taken along line 2—2 as shown in Fig. 1.

Fig. 3 is a bottom plan view of the plug cap portion of the socket.

Fig. 4 is a cross-sectional view taken on

line 4—4 in Fig. 1 showing the contact of the jumper with one end of the resistance unit.

Figs. 5 and 6 are fragmentary cross-sectional views showing the jumpers in contact with the mid-portion and the other end of said resistance unit respectively.

Fig. 7 is a perspective view of the resistance element with the parts partially unfolded, and the resistance wire partially wound therein.

Fig. 8 is a front elevational view of the improved dimming lamp socket.

Referring in detail to the drawing, 10 denotes a detachable type of dimming socket 60 embodying the invention, the main elements of which are connected to and supported by a plug 11 made of suitable insulating material and provided with a central contact 12.

The contact 12 includes a screw 12^a, the shank of which extends axially through a central bore in said plug, the head of the screw preferably being set into a washer 12^b which is set in a suitable recess 11^a provided in the end of the plug 11, as is clearly shown 70 in Fig. 2. A threaded brass shell 13 which forms the outer contact encloses the plug 11 and has lips 13^a projecting inwardly from the inner end thereof against the bottom of the plug. The plug 11 is mounted centrally to extend up from a cap portion 14 made of a suitable molded insulating compound, such as a phenol condensate compound, porcelain or the like material. Said plug is rigidly secured in position by the 80 screw 12 which has its threaded end projected through the top of the cap portion 14 and into a recess 14^a formed on the underside of said cap portion. Said screw end is provided with a clamping nut 15.

For connecting the plug contacts with the current carrying parts of the socket, a spring member 16 having one end thereof anchored to the threaded end of the screw 12^a by means of the nut 15, provides one connecting contact, 85

90

and an extension 13^b on one of the lips 13^a passing through the top of the cap and into said recess 14^a provides the other connecting contact, as shown in Figs. 2 and 3.

The cap portion 14 is demountably secured to a body portion 17, said body portion being likewise formed of a molded insulating compound similar to that of the cap portion. For holding said casing portions together to form a non-metallic casing for the current carrying parts of the socket, the dimming means and its control, there is embedded in the top side of the body portion 17 a plurality of spaced threaded anchoring thimbles 18 which receive fastening screws 19 inserted from the top of the cap portion 14, as is clearly shown in Figs. 1 and 2. The free or lower end of the body portion 17 forms a housing about a screw receptacle shell 20 which is adapted to connect with the base of a standard lamp (not shown). To retain said shell in its housing an inturned flange 20^a is provided at the inner end of said shell. Said flange is perforated to receive screws 21 which may be inserted through the body portion 17 from the top side thereof. The screws 21 have a threaded engagement with a washer nut 22 which lies flat against the shell flange 20^a, thus rigidly clamping the shell 20 to the body portion 17. (See Fig. 2.)

The shell 20 on its inner end, adjacent the flanges 20^a, has an opening sufficiently large to receive an integral boss 17^a projecting centrally down from the body portion 17 into said shell 12 so as to form an insulated support for an inner spring central contact member 23 for the lamp receptacle shell 20. For rigidly securing said contact member 23 in place, there is provided an axial extending screw 24. The lower or head end 24^a of the screw 24 serves to anchor one end of said contact member 23 to the boss 17^a, as shown in Fig. 2. The upper end of said screw 24 extends beyond the top side of the body portion 17 and is provided with a spacing washer 25 and a collar nut 26 between which is pivotally mounted on said screw 24, a lever arm 27 of a dimming control mechanism.

The lever arm 27 is preferably made of insulating material, such as sheet fibre or mica and has its actuating end 27^a secured in any suitable manner to a pull-chain 28. As here shown, the chain 28 is adapted to ride in an arcuately shaped groove 17^b formed in the upper surface of the body portion, said groove extending concentrically with respect to the pivoting point about which said lever arm swings and terminating with diametrically opposed openings 17^c through which the ends A and B of the chain 28 pass, as is clearly shown in Figs. 1 and 8, respectively. The fastening of the lever arm 27 to the chain 28 may comprise a strap 29 having one end secured to said arm by means of eyelet rivets 30 and having the other end securely at-

tached to the links of the chain in any suitable manner, as at 31. The opposite or switch end of the lever may have securely mounted thereon a spring blade 32 by means of an eyelet rivet 33. Said blade is secured by the collar nut 26 to connect with the central spring contact member 23 of the lamp receptacle through the screw 24. The switch blade 32 is adapted to contact with the heads 34^a, 35^a, 36^a and 37^a of the screws 34, 35, 36 and 37, respectively, said screws being arranged in concentric alignment with respect to the pivoting point about which said lever swings. Said screws preferably are secured in position by engaging with anchoring thimbles 38 embedded in the top side of the body portion 17. The screw heads 35^a, 36^a and 37^a serve as switch terminal contact posts for one end of each of the jumpers 39, 40 and 41, respectively, the other ends of said jumpers being positioned to contact with one end 42^a, a mid-portion 42^b, and the other end 42^c of resistance unit 42 respectively. Said resistance unit may be of any suitable construction but preferably comprises a resistance wire 42^d wound on a strip 42^e of sheet mica, said strip being folded over on itself and having insulating strips 43 interposed between the adjacent folded portion, as shown in Fig. 7. After being thus folded, the unit 42 is formed into a compact body and is fitted into a recessed pocket 17^c formed in the top of the body portion 17 in spaced concentric alignment with said screws 34, 35, 36 and 37, as is clearly shown in Fig. 1. The ends of the jumpers 39, 40 and 41 may connect with the unit in any suitable manner, preferably making a clamping contact with the resistance wires at 42^a, 42^b, and 42^c. To insure good contact between said jumpers and said unit, the latter is tightly wedged in the pocket 17^c, as is clearly shown in Figs. 4, 5 and 6. Where the jumpers 42^b and 42^c pass the resistance wires in the adjacent folded portions of the unit, insulating strips 44 may be provided. See Figs. 5 and 6.

As seen from Figs. 1 and 2, the heads 21^a of the screws 21 preferably project above the top of the body portion 17 and serve as stops for limiting the swinging movement of the lever arm 27. One of said heads 21^a is adapted to form a contact for detachably engaging with the end of the spring member 16 to electrically connect the central contact 12 with the lamp socket 20. Another detachable connection is provided by anchoring a spring member 45 to project upwardly from the screw head 37^a, said member being adapted to contact with the extension 13^b for electrically connecting the shell contact 13 with the resistance unit 42.

From the foregoing description and drawings, it is apparent that the parts of the device are readily assembled to facilitate large scale production and yet provide a compact,

rugged structure which is relatively cheap to manufacture. It should be noted that the cap portion 14 can be easily dismounted from the base portion to facilitate assembly of the socket 10, the circuit current carrying parts through said socket being detachably secured together to permit easy separation through the spring contact connection of the member 16 with the screw head 21^a and the shell contact extension 13^b with the spring member 45.

The operation of the dimming socket 10 will now be readily understood. With the parts assembled as shown in the drawing, and plug contacts connecting with a suitable electric power source in the well understood manner, a pull exerted on the end A of the chain 28 (see Fig. 1) will cause the lever arm 27 to swing into contact with the screw head 37. The receptacle shell 20 will then be in direct connection with the plug contacts 12 so that a lamp (not shown) connected in said shell will receive full power from the supply source and will produce its maximum illumination. By releasing the chain end A and applying a slight pull on the other end B, the lever arm will swing the switch blade 32 into contact with the screw head 36^a. This operation of the dimming mechanism inserts a portion of the resistance of unit 42 in circuit between the plug contacts and the lamp receptacle and is effective to reduce the current flowing to the lamp, thereby causing a diminution of the light emitted from the lamp in the socket receptacle. Swinging the lever arm 27 so that the switch blade 32 contacts with the screw head 35^a by further pulling the chain end B, cuts in the entire resistance of unit 42 and further dims the light from the lamp in the receptacle socket. By pulling the chain end B to its maximum downward position, the lever arm 27 swings into contact with the screw head 34^a opening the circuit to the socket 10 and cutting off the power to the lamp receptacle thereby extinguishing the lamp. To relight the lamp and adjust the illumination, the chain end A is pulled for moving the lever arm 27 to vary the resistance in circuit with the lamp socket.

It will thus be seen that there is provided a device in which the several objects of this invention are achieved, and which is well adapted to meet the conditions of practical use.

As various possible embodiments might be made of the above invention, and as various changes might be made in the embodiment above set forth, it is to be understood that all matter herein set forth or shown in the accompanying drawing is to be interpreted as illustrative and not in a limiting sense.

Having thus described my invention, I claim as new and desire to secure by Letters Patent:—

1. A dimming socket of the character de-

scribed having a casing of insulating material molded with a socket portion having an end wall and a pocket in said wall, an adjustable resistance unit wedgingly fitted into said pocket, control means for varying the resistance of said unit including a movable contact arm, spaced terminal switch contacts and jumpers, one end of each jumper being connected to a contact, the other ends of each of said jumpers clampingly engaging with said unit on wedging the latter in said pocket. 70

2. In a socket of the character described, a casing made entirely of insulating material, said casing being formed with a pocket, and a dimming unit comprising a strip of insulating material and a resistance wire wound on said strip and jumpers connected to spaced contacts, said unit being folded to form a compact body and wedged into said pocket whereby the ends of the jumpers contacting with said wire are clampingly secured in position. 80

3. A dimming socket of the character described having a casing made entirely of insulating material, said casing being formed with a pocket, a resistance unit fitted into said pocket, said unit comprising a strip of insulating material and a wire wound on said strip, said unit being folded to form a compact body, and jumpers, said unit being wedged into said pocket with the ends of the jumpers contacting with said wire for clampingly securing the jumpers to the wire. 90

4. A dimming socket of the character described, comprising a casing of insulating material molded with a socket portion having an end wall and an arcuate pocket in said wall, an adjustable resistance unit frictionally fitted into said pocket, a plurality of contacts mounted on said wall, jumpers connecting said contacts with spaced points on said unit, a cap member removably secured to said casing in overlying relation to said end wall, and a movable contact arm mounted on the underside of said cap and adapted to movably contact said contacts. 100

5. A dimming socket of the character described comprising a casing of insulating material molded with a socket portion having an end wall and an arcuate pocket in said wall, an adjustable resistance unit frictionally fitted into said pocket, a plurality of contacts mounted on said wall, jumpers connecting said contacts with various points on said unit, a cap member removably secured to said casing in overlying relation to said end wall, a movable contact mounted on the underside of said cap and adapted to movably contact said contacts, and a plug secured to said cap on the outer side thereof, a shell fitted on said plug, said shell having a portion extending through said cap for electrical contact with one of said contacts. 115

6. A dimming socket of the character described having a casing of insulating ma-

terial molded with a socket portion having an end wall and an arcuate pocket in said wall, and an adjustable resistance unit frictionally fitted into said pocket, said unit comprising a folded strip of insulating material, a wire wound on said strip and insulating material between adjacent folded portions of said strip.

In testimony whereof I affix my signature.

19 HARRY HERTZBERG.
